INSECTICIDE

Allen H. Lewis, Berkeley, Calif., assignor, by
mesne assignments, to California Research Cor-
poration, San Francisco, Calif., a corporation
of Delaware

No Drawing. Application July 27, 1943,
Serial No. 496,310

2 Claims. (Cl. 167—24)

1

This invention relates to improved insecticidal compositions containing plant extracts, such as pyrethrum and rotenone, in combination with aromatic sulfonamides.

It is well known that certain plant extracts such as pyrethrum, rotenone, etc. have the property of paralyzing and killing many species of insects by contact. They are widely used as the toxic element of insecticides, usually along with inert material which serves as vehicle, spreader, or diluent, as for example in solution in kerosene.

I have discovered that, although as a rule sulfonamides by themselves have comparatively little toxic effect, the addition of certain sulfonamides greatly increases the toxicity of these plant extracts. My discovery thus makes possible the production of insecticides of very high potency without the use of prohibitive amounts of costly plant extracts. It also provides a means of reducing the consumption of plant extract without loss of toxic efficiency.

The compounds which I have discovered which have the property of activating the insecticidal effect of pyrethrum, rotenone, etc., and which I refer to as aromatic sulfonamides, are aromatic sulfonic acid amides of the type represented by the following general formula:

in which R_1 is an aryl or alkaryl radical, R_2 is a hydrogen atom or a hydrocarbon residue, and R_3 is a hydrocarbon residue.

I also include compounds of the above general type in which the nitrogen is a part of a heterocyclic ring. Such compounds may be represented by the general formula:

in which R_4 is a heterocyclic ring containing nitrogen, attached to the sulfur atom by a sulfur to nitrogen bond.

Examples of effective compounds of the type represented above are those in which the radicals are:

2

R_1 : phenyl
tolyl

R_2 : hydrogen
an alkyl radical having from 1 to 6 carbon atoms

R_3 : an alkyl radical having from 1 to 6 carbon atoms
phenyl
tolyl

10 R_4 : N-piperidyl
N-1,2,3,4-tetrahydroquinolyl
N-morpholiny

In addition to the above I have found that effective compounds of this type are those in which 15 R_1 is derived from highly aromatic petroleum fractions or extracts. I have also found that highly effective sulfonamides are those in which R_4 consists of reduced (hydrogenated) nitrogen bases such as those obtained from petroleum fractions or from coal tar. The weak bases which have heretofore been extracted from light petroleum distillates are of the nature of tertiary amines. They may be reduced, as by catalytic hydrogenation, to what may be termed secondary amines. "Reduced nitrogen bases" as used herein refers to products of this nature. One method of preparing these bases is described in U. S. Patent No. 2,302,655.

Some of the aromatic sulfonamides typical of 30 those described generally above and which have been found to produce an excellent toxic activation of pyrethrum, rotenone, etc. are: o- and p-toluene sulfonyl di-n-butyl amide; o- and p-toluene sulfonyl reduced-nitrogen-base; benzene 35 sulfonyl reduced-nitrogen-base; p-toluene sulfonyl methyl p-toluidide; p-toluene sulfonyl tetrahydro quinolide; p-toluene sulfonyl morpholide.

In general the sulfonic acid amides of the type 40 described may be prepared by the reaction of amines or ammonia with sulfonic acid chlorides. The reactants are selected and combined so as to result in a sulfonic acid amide having the indicated general formula. For example, o-toluene sulfonyl di-n-butyl amide may be prepared by reacting o-toluene sulfonyl chloride with di-n-butyl amine.

An example which illustrates the method of 45 preparation of a suitable sulfonamide from an aromatic extract of petroleum and reduced nitrogen bases from petroleum is as follows: 230 parts

of a low aniline point petroleum thinner of 190°-280° F. boiling range were added slowly to 800 parts of chlorosulfonic acid. The temperature of the reaction was held at about 40° F. and the mixture stirred for 12 hours. The reaction mixture was then poured onto ice. 207 parts of aromatic sulfonyl chloride separated as a heavy liquid and was washed with water and dried. 200 parts of reduced nitrogen bases obtained by the catalytic hydrogenation of nitrogen bases extracted from California petroleum were dissolved in 250 parts of petroleum ether. 100 parts of the aromatic sulfonyl chloride were added at a maximum temperature of 130° F. and the mixture agitated for 1 hour followed by water washing and distillation to remove hydrochloric acid and petroleum ether. 130 parts of a heavy red liquid were thus obtained consisting of aromatic sulfonyl substituted-piperidides.

The following is an example, for illustrative purposes, of an insecticidal composition using an aromatic sulfonamide in combination with pyrethrum according to my invention: 3 parts by volume of p-toluene sulfonyl di-n-butyl amide and 2.5 parts of a 20:1 commercial pyrethrum extract were dissolved in kerosene to a total volume of 100 parts, giving a solution containing 3 per cent by volume of the sulfonamide and a total pyrethrin concentration of 50 milligrams per 100 cc. This solution was tested as a spray according to the standard Peet-Grady large group method on four different cultures of flies. 100% of the flies were paralyzed at the end of ten minutes and 69% were dead at the end of 24 hours.

The effect of the use of the sulfonamide in this spray is clearly shown by the fact that a control spray containing the same amount of pyrethrum in the same kerosene, but containing no sulfonamide, paralyzed 99.7% of the flies in 10 minutes while giving only 11.4% kill at the end of 24 hours. That the increased toxicity of the combination spray was not due to the additive toxicities of the ingredients is shown by the fact that a kerosene solution containing 3% by volume of p-toluene sulfonyl di-n-butyl amide alone gave zero knock-down in 10 minutes and only 8% kill at the end of 24 hours.

Similarly, the p-toluene sulfonamide from reduced petroleum nitrogen bases, when added in the proportion of 3% by volume to a kerosene containing 2.5 percent of a 20:1 pyrethrum extract, raised the 24-hour kill from 13.4% to 77.4%. Addition of this sulfonamide to kerosene containing 0.5% by volume of derris root (rotenoid) extract raised the 24-hour kill from 47.4% to 61.4%. When 3% of this sulfonamide was tested by itself in kerosene it gave only a 6% kill, which is approximately the result obtained from the use of highly treated kerosene alone.

In like manner other sulfonamides (in a 2.5% solution of pyrethrum 20:1 extract in kerosene) gave the following results:

	Percent	
o-Toluene sulfonyl di-n-butyl amide (3% vol.)	kill	86.2
o-Toluene sulfonyl reduced N-bases (2% vol.)	kill	83.4
Benzene sulfonyl reduced N-bases (3% vol.)	kill	88.4
p-Toluene sulfonyl methyl toluidide (3% vol.)	increase in kill	63.1

The above data, obtained under the most

rigorous test conditions, exemplify the powerful activating effect of the aromatic sulfonamides on pyrethrins and rotenoids.

The concentrations of toxic agent and sulfonamide activator may be varied as desired, it being understood, however, that the primary value of the compounds described lies in their ability to activate the toxicity of the plant derivatives, and therefore this value will largely disappear if the concentration of plant derivative is too low. In the case of pyrethrum 20:1 extract in kerosene this practical minimum is about 1% by volume.

The following illustrates the effect on toxicity of varying the concentration of plant extract (in this case pyrethrum 20:1 extract) and sulfonamide (in this case p-toluene sulfonamide of reduced nitrogen bases) in a kerosene spray:

	Concentration, vol. per cent		N. A. I. D. M. Rating
	Pyrethrum 20:1 extr.	Sulfonamide	
1	1.5	3.0	+17
2	2.5	2.0	+10
3	2.5	3.0	+26
4	2.5	3.5	+38
5	4.0	2.0	+26
6	5.0	0.0	±0
7	10.0	0.0	+25

Comparison of (3), (5) and (7) shows the amount of pyrethrum extract replaceable by this sulfonamide without loss of toxic effect.

While the examples given herein relate to spray type compositions in which kerosene has been used as the solvent and dispersing agent or vehicle, it is to be understood that my plant extract-sulfonamide combination may be used with other spreading, diluting or carrying materials.

I claim:

1. An insecticidal composition comprising as its principal toxic ingredient pyrethrum and the benzene sulfonic acid amide from the reduced nitrogen bases from petroleum.

2. An insecticidal composition comprising as its principal toxic ingredient a contact insecticide selected from the class consisting of pyrethrum and rotenone, and an aromatic sulfonic acid amide of the type

in which R_1 is a mononuclear aryl radical and R_4 is a heterocyclic ring containing nitrogen joined to the sulfur by a sulfur to nitrogen bond which ring has been derived from reduced nitrogen bases from petroleum.
